moriat.

UNITED STATES PATENT OFFICE.

CHARLES C. BIER, OF NEW ORLEANS, LOUISIANA.

IMPROVED IRON TIE FOR COTTON-BALES.

Specification forming part of Letters Patent No. 28,825, dated June 23, 1860.

To all whom it may concern:

Be it known that I, CHARLES C. BIER, of New Orleans, parish of Orleans, State of Louisiana, have invented a new and simple mode of making an iron tie or buckle, for the better security in fastenings of cotton-bales and all other baled goods, and for the protection of the same from damage by rust; and I do hereby declare that the following is a full, clear, and exact description of the construction and operation of the same, reference being had to the annexed drawings, making a part of the specification, in which—

Figure 1 is a perspective view; Fig. 2, loop part of the tie or buckle; Fig. 3, the band; Fig. 4, illustrates the manner of putting the tie or buckle together; Fig. 5, the triangular pin.

Letters in all have the same reference to parts.

To enable others skilled in the art to make and use my invention, I will proceed to describe its construction and operation.

I make a square rim, as at A, of any known metal of sufficient thickness to stand whatever strain may be put upon it by the nature of goods baled. Then take a band of iron or any other metal of a sufficient breadth and thickness to overcome the strain intended to stand. On one end of the band C, I rivet the pin D, as at B, Fig. 3. This pin, Fig. 5, is made trian-

gular, (and which also may be made round.) The band is half the width of the buckle, and the pin D is the width of the buckle, Fig. 2. I then clean and tin or galvanize all the parts in the usual or any known way of doing the same, for the better protection of cotton and other baled goods from damage by rust.

Fig. 4 illustrates the manner of putting the tie together. When the bale is pressed to the size required, the bands C are put around in the usual way. Then slip the buckle A over the end C. Then bring the end B D under through A, as Fig. 4. Now bring the buckle A around to B, then slip the end C through A over D, and the tie is made, as at Fig. 1. The greater the strain on the bands the tighter the tie will be, for as the ends recede from each other the end B is brought up to A, thereby wedging the end C tight, and so prevent its slipping.

What I claim as my invention, and desire to secure by Letters Patent, is—

The particular novel mode of making an iron tie for the purpose of securely fastening cotton bales or other baled goods, as herein described, using for the manufacture of the same any metal suitable for that purpose.

CHARLES C. BIER.

In presence of—

JAS. GRAHAM,
HUGH MADDEN.
